Issue Feb 28 1871

United States Patent Office.

MATHEW F. BOLAND, OF PHILADELPHIA, PENNSYLVANIA.

Design No. 4,701, dated March 14, 1871.

DESIGN FOR HAME-TOPS.

The Schedule referred to in these Letters Patent and making part of the same.

I, MATHEW F. BOLAND, of the city of Philadelphia and State of Pennsylvania, have invented and produced a new and original Design for Hame-Tops, of which the following is a specification.

The nature of my invention is fully illustrated in the accompanying photographic illustrations, to which reference is made.

The photographs represent a hame having the main and wooden part A constructed in the usual manner.

In connection with the part A is a metallic top, B, of elliptical form in its cross-sections, as represented.

What I claim as my invention is—

The design for hame-top, as shown in the accompanying photographic illustrations.

MATHEW F. BOLAND. [L. S.]
